UNITED STATES PATENT OFFICE.

GEORGE J. RACKHAM, OF CHICAGO, ILLINOIS, ASSIGNOR TO YELLOW COACH MANUFACTURING COMPANY, OF CHICAGO, ILLINOIS, A CORPORATION OF ILLINOIS.

RADIATOR FILLER CAP AND THE LIKE.

Application filed September 24, 1923. Serial No. 664,526.

To all whom it may concern:

Be it known that I, GEORGE J. RACKHAM, a subject of the King of England, residing at Chicago, in the county of Cook and State of Illinois, have invented certain new and useful Improvements in Radiator Filler Caps and the like, of which the following is a specification.

This invention has to do with certain improvements in radiator filler caps and the like, and has reference particularly to improvements in radiator filler caps for radiators of automobiles and other motor vehicles.

One of the objects of the present invention is to provide a filler cap of such construction that it can be very easily opened or closed by the operator. In this connection a further object is to provide an arrangement such that the act of locking or unlocking the filler cap may be performed by turning the proper element through only a quarter revolution or less.

In connection with the foregoing, a further object is to provide a construction such that when the filler cap is turned into closed position it will be held there securely in the sealed condition under spring pressure, so as to provide the desired seal. In this connection, a further object is to provide an arrangement such that the cap proper will engage the stationary neck or sleeve with a wedging or tapering engagement so as to insure a substantially steam tight connection.

A further object of the invention is to provide an arrangement such that in case of the generation of an excessive amount of steam pressure within the radiator, as, for example, in case the overflow passage should become stopped up, the cap proper can yield a slight amount so as to allow for the escape of steam.

A still further object of the invention is to provide an arrangement such that when the cap is turned into open position a very large and full opening will be provided so as to allow the radiator to be easily and rapidly filled. Other objects and uses of the invention will appear from a detailed description of the same, which consists in the features of construction and combinations of parts hereinafter described and claimed.

In the drawings:

Figure 1 shows a vertical section through

a filler cap and radiator neck embodying the features of the present invention, the cap being shown in the open position by means of dotted lines;

Fig. 2 shows a plan view corresponding to Fig. 1;

Fig. 3 shows a section taken on line 3—3 of Fig. 1 looking in the direction of the arrows;

Fig. 4 shows a section taken on line 4—4 of Fig. 1 looking in the direction of the arrows;

Fig. 5 shows a fragmentary vertical section taken on line 5—5 of Fig. 3 looking in the direction of the arrows; and

Fig. 6 shows an end view of the cross locking bar.

In the construction illustrated in the drawings, the radiator neck, which is designated by the numeral 7, is provided in its lower portion with a series of webs or flanges 8 which support a central collar 9, by means of which the entire neck may be drawn solidly down onto the radiator as by means of a stud 10. Around its upper end the neck is provided with a tapered circular seat 11, the same being preferably ground and tapering at an angle of 60° to the horizontal or thereabouts.

The neck 7 is provided at one side with a lug 14 which is pivoted between the ears 13 and 15 of the cap. This pivotal connection is somewhat loose, so that the cap can adjust its position slightly in order to come to a firm even seat. In its lower portion the cap is provided with a downwardly depending circular flange 16, whose outer edge is beveled and preferably ground so as to come to an even seat against the seat 11. The entire cap can be turned back into the position of the dotted lines of Fig. 1, so as to provide a large clear opening to the neck 7.

Extending downwardly from the central portion of the cap 12 is a pocket 17, the lower end 18 of which is slightly contracted in size so as to establish a seat for the lower end of a spiral spring 19. A stem 20 is extended loosely through the pocket 17, the upper end of said stem 20 carrying a head 21 on which may be placed a symbol plate 22 or the like. The lower end of the stem 20 carries a cross bar 23 whose upper surface is preferably tapered or of V-shaped cross section, as shown at 24 in Fig. 6. In the particular construction illustrated, the symbol member 22 has a down-

wardly depending stem 22^a, the lower end of which receives a nut 22^b which serves to draw the cross bar 23 firmly against the lower end of the stem 20. The exact construction of the stem 20 and its lower end of the cross bar 23 is largely a matter of design, but it will be observed that in the arrangement illustrated the lower edge of the head 21 establishes a shoulder against which the upper end of the spring 19 bears. Consequently, said spring serves effectively to tend to raise the cross bar 23 with respect to the cap 12. Extending inwardly from the front and rear faces of the upper portion of the neck 7 are lugs 24 and 25 respectively, which lugs are segmental in form. The lower faces of these lugs are recessed, as shown at 26 in Fig. 5, so that when the cross bar 23 comes into the proper locking position its end portions will snap into these recesses and thus tend to prevent rotation of the cross bar, together with the stem 20 and symbol 22. Upon turning the symbol 22 through something less than a quarter revolution, the bar 23 will turn with it a sufficient distance to be completely disengaged from the lugs 24 and 25 so as to free the cap 12 and thus allow it to be turned back to open the neck. The presence of the spring 19 serves not only to draw the cap 12 home under sufficient pressure to insure a tight closure, but also permits the necessary amount of yield of the bar 23 to insure engagement or disengagement with the lugs 24 and 25, as the case may be; and said spring also will allow the necessary amount of yield to permit of the escape of steam if necessary in order to avoid generation of excessive pressure within the radiator.

While I have herein shown and described only a single embodiment of the features of my present invention, still I do not limit myself to the same except as I may do so in the claims.

I claim:

1. In a device of the class described, the combination of a vertical neck having in its upper portion a circular tapered seat, a pair of oppositely disposed inwardly projecting lugs on the upper portion of said neck having their lower faces upwardly recessed, a cap having in its bottom portion a downwardly depending circular tapered flange adapted to engage the seat aforesaid, a loosely yieldable pivotal connection between the cap and the upper portion of the neck, a downwardly depending central pocket in the upper portion of the neck, having its lower end turned inwardly to establish a shoulder for the support of a spring, a stem loosely extending through said pocket, a spring within the pocket surrounding the stem and having its lower end engaging the shoulder aforesaid and its lower end en-

gaging the upper portion of the stem, a cross bar on the lower end of the stem, having the upper surfaces of its end portions wedge shaped and adapted to engage the recesses of the neck lugs, and a symbol connected to the upper portion of the stem and adapted to occupy a position across the vehicle when the bar is in engagement with the lugs aforesaid, substantially as described.

2. In a device of the class described, the combination of a vertical neck having in its upper portion a circular tapered seat, a pair of oppositely disposed inwardly projecting lugs on the upper portion of said neck and having their lower faces recessed, a cap having in its bottom portion a downwardly depending circular tapered flange adapted to engage the seat aforesaid, a loosely yieldable pivotal connection between the cap and the upper portion of the neck, a vertical stem extending through the cap and slidably and rotatable therein, a spring normally tending to raise such stem, a cross bar on the lower end of the stem having the upper surfaces of its end portions wedge shaped and adapted to engage the recesses of the neck lugs, and a symbol connected to the upper portion of the stem and adapted to occupy a position across the vehicle when the bar is in engagement with the lugs aforesaid, substantially as described.

3. In a device of the class described, the combination of a vertical neck having in its upper portion a circular tapered seat, a pair of oppositely disposed inwardly projecting lugs on the upper portion of said neck and having their lower faces upwardly recessed, a cap having in its bottom portion a downwardly depending circular tapered flange adapted to engage the seat aforesaid, a loosely yieldable pivotal connection between the cap and the upper portion of the neck, a stem extending through the cap and slidably and rotatable with respect thereto, a cross bar on the lower end of the stem having the upper surfaces of its end portions wedge-shaped and adapted to engage the recesses of the neck lugs, and means for drawing the stem upwardly with respect to the cap, substantially as described.

4. In a device of the class described, the combination of a vertical neck having in its upper portion a circular tapered seat, a pair of oppositely disposed inwardly projecting lugs on the upper portion of said neck, a cap having in its bottom portion a downwardly depending circular tapered flange adapted to engage the seat aforesaid, a loosely yieldable pivotal connection between the cap and the upper portion of the neck, a stem extending through the cap and slidably and rotatable with respect thereto, a cross bar on the lower end of the stem adapted to engage the lugs aforesaid, and

means for drawing the stem upwardly with respect to the cap, substantially as described.

5. In a device of the class described, the combination of a vertical neck having in its upper portion a tapered seat, a pair of oppositely disposed inwardly projecting lugs on the upper portion of said neck, a cap having in its bottom portion a down-

wardly depending tapered flange adapted to 10 engage the seat aforesaid, a stem extending through the cap and slideable and rotatable with respect thereto, a cross bar on the lower end of the stem and adapted to engage the lugs aforesaid, and means for drawing 15 the stem upwardly with respect to the cap, substantially as described.

GEORGE J. RACKHAM.
